UNITED STATES PATENT OFFICE.

LOUIS W. SOUTHGATE, OF WORCESTER, MASSACHUSETTS, ASSIGNOR TO THE CAMPBELL PRINTING PRESS & MANUFACTURING CO., OF NEW YORK, N. Y., A CORPORATION OF NEW YORK.

MULTICOLOR-PRINTING MACHINE.

No. 851,038.

Specification of Letters Patent.

Patented April 23, 1907.

Application filed January 19, 1900. Renewed July 28, 1906. Serial No. 328,246.

To all whom it may concern:

Be it known that I, LOUIS W. SOUTHGATE, a citizen of the United States, residing at Worcester, in the county of Worcester and State of Massachusetts, have invented a new and useful Multicolor-Printing Machine, of which the following is a specification.

It has been proposed in the art to make reciprocating-bed multicolor-printing machines. The devices that have been previously proposed have been open to one or both of two objections. The first objection to the prior devices is that an extremely long length of stroke is necessarily given to the reciprocating bed. This makes an awkward mechanism and necessarily limits the speed of the machine. The second objection found in the prior devices is that the color-design plates which are to control the supply of the various colored inks have been mounted on separate carriers. This in some instances gives the plates too much curvature and in every case that I know of tends to complication and affects the register.

The aim of this invention is to provide a reciprocating-bed multicolor-printing machine which shall overcome these objections by having a short or usual stroke of bed and by having a construction in which the color-design plates are necessarily set to register with each other.

To this end the invention consists in providing any of the ordinary forms of reciprocating-bed presses with a color-design-plate cylinder capacitated to receive a plurality of color-design plates circumferentially, separate inking apparatuses coöperating with said color-design-plate cylinder for each color-plate, and with a transfer-cylinder on which the colors are registered together circumferentially and axially to make up a positive of the multicolor imprint and which applies the positive to the printing-form carried by the bed.

The parts are preferably so arranged that the color-design-plate cylinder will be continuously driven in one direction, the transfer-cylinder geared thereto and moved up and down so as to contact with the form on the bed as the latter moves in one direction and to clear the form as the bed moves in the opposite direction.

I may either arrange the color-design-plate

cylinder to carry another plate to supply the black ink, or I may use a separate device for this purpose.

In the preferred form of my apparatus I use the ordinary two-revolution cylinder reciprocating-bed press with a back delivery, arrange the color-design-plate cylinder and its appurtenances front of the impression-cylinder, and provide cam mechanism for controlling the transfer-cylinder. By this arrangement I can make a rapid machine and one in which the color-design plates will register with each other, as they are all carried by the same part.

In the accompanying three sheets of drawings I have shown enough of a printing-machine constructed according to this invention to enable a skilled mechanic to practice the same.

Referring to the drawings, Figure 1 is a sectional elevation of an ordinary two-revolution printing-press having my improvement applied thereto. Fig. 2 is a view similar to Fig. 1, the impression-cylinder having made one turn from the position shown in Fig. 1. Figs. 3 and 4 are views similar to Figs. 1 and 2, illustrating a modified form of the device. Fig. 5 is an enlarged plan, and Fig. 6 is an enlarged end elevation, of the color-design-plate cylinder, showing how the color-design-plate-inking rolls are arranged and controlled. Fig. 7 and Fig. 8 are an enlarged partial sectional and end view, respectively, illustrating the mounting of the transfer-cylinder.

Referring to the drawings and in detail, A designates an impression-cylinder, and B a bed of an ordinary two-revolution printing-press. The impression-cylinder A has the usual grippers a. The form b to make the impression on the sheet is placed on the bed in the usual way.

C designates the feed-board.

The device has any of the usual back deliveries—as, for example, delivery-cylinder D, strippers E, and tapes F. By this mechanism sheets can be presented by the impression-cylinder in the ordinary manner and printed from the form b. In front of the impression-cylinder I arrange a color-design-plate cylinder G. This color-design-plate cylinder is preferably made of the same size as the impression-cylinder and is preferably geared to make turn for turn with the impres-

sion-cylinder, but in the opposite direction thereto, as indicated by the arrows. As shown in the first sheet of the drawings, the color-design-plate cylinder is arranged to carry 5 circumferentially three color-design plates g^1 , g^2 , and g^3 . Three ink-fountains H^1 , H^2 , and H^3 are arranged in position around the plate-cylinder. Ink is taken from these fountains by transfer-rollers h^1 , h^2 , and h^3 to distributer-10 rollers j^1 , j^2 , and j^3 and from the latter to color-design-plate-inking rollers k^1 , k^2 , k^3 , and k^4 . The plate-inking rollers are mounted in suitable arms 10, pivoted or journaled on the shafts of the distributers. 15 Hooks 11 engage these arms and connect by springs 12 to studs 13, so that the plate-inking rollers are pulled toward the center of the color-design-plate cylinder. Each plate-inking roller is provided with a wheel or isk 20 130. The ends of the plate-cylinder are provided with cams or controlling-grooves 14, 15, and 16 for these wheels. By this arrangement each set of plate-inking rollers will only coat with one plate. By this construction if a different-colored ink is put in 25 each fountain each plate will receive a separate colored ink. L designates a transfer-cylinder which has a circumference of one-third the circumference of the color-design-30 plate cylinder or a circumference substantially equal to the circumferential length of each color-design plate, so that the colors are registered together circumferentially and axially thereon to make up a positive of the 35 multicolor imprint, which positive is applied to the printing-plate. The colors may be blended also, if desired, by overlapping the designs or relief-surfaces of the color-design plates. This transfer-cylinder is provided 40 with a soft or receptive surface adapted to take the ink from the color-plates. This transfer-cylinder is mounted in arms 17, which are pivoted on the stationary quills 18. A shaft 19 is journaled in each of said quills 45 and is driven by a gear 20, which meshes with the large driving-gears of the plate-cylinder. On the inner end of the shafts 19 are arranged gears 21, which by means of intermediates 22, mounted on studs projecting in from said 50 arm 17, turn the gears 23 on the shaft of the transfer-cylinder. By this gearing the transfer-cylinder will be turned so as to have the same peripheral speed as the color-design-plate cylinder. The same is also capable of a 55 rising-and-falling motion about the quills 18 as pivots.

The transfer-cylinder is raised and lowered by means of suitable cams, which connect by yokes 26 to said arms 17. These yokes carry 60 rolls which bear on the cams, and the rolls are normally kept in contact therewith by springs 27. The cams are geared to make one turn for each cycle or each two revolutions of the impression-cylinder. If the 65 color-design-plate cylinder is capacitated to

receive three color-design plates circumferentially, I preferably provide a mechanism back of the impression-cylinder to supply black ink to the form. This mechanism consists of a fountain H^4 and a ductor h^4 , which 70 carries ink to a distributor j^4 , which supplies ink to the plate-rollers k^4 . A plate-carrying cylinder M is arranged as shown, and the same is provided with a plate g^4 , having a circumferential length equal to the form. A 75 transfer-cylinder L' is mounted in suitable arms 28, hung on the shaft of the cylinder M. These arms are controlled by cams 29, which connect by yokes thereto, and the rollers on the yokes are held against the cams by suitable 80 springs 31. The cams 29 are geared to make turn for turn with the cams 34.

With this arrangement the operation is substantially as follows: As the color-design-plate cylinder G turns each color - design 85 plate carried thereby will receive a supply of ink of the color the plate is designed for. The plates are prepared so that when the designs of the same are superimposed the desired multicolor impression will be obtained. 90 The transfer-cylinder L is held up in contact with the color-design-plate cylinder G for at least a full revolution thereof, so that said transfer-cylinder will receive the design of each color-design plate in the appropriate 95 ink and so that the colors will be registered thereon circumferentially and axially to make up a positive of the multicolor imprint. Then the transfer-cylinder is lowered to contact with the printing-form on the bed, and 100 by this arrangement the design of all the color-design plates will be transferred, properly registered, and blended, if desired, to the printing-form. The transfer-cylinder is arranged to contact with the form only as the 105 bed moves in one direction, preferably on the forward stroke. Then as the bed moves forward under the impression-cylinder the sheet will receive the multicolor design. When the bed passes back of the impression-cylinder, the transfer-cylinder L' will apply 110 in black ink the design of plate g^4 , which is properly prepared for this purpose. In this way a multicolor impression having such parts thereof in black as desired can be made 115 upon the sheet.

In the second sheet of drawings the color-design-plate cylinder G is made large enough to carry in addition the plate g^4 , which controls the supply of black ink, and the four 120 ink-fountains are arranged in coöperative relation with this cylinder. This is the preferred form of construction. This device works the same as before described, except that the transfer-cylinder L applies the black 125 ink as well as the colored inks to the printing-form. If desired, this form of machine may be arranged to receive any of the ordinary inking apparatuses at the back of the impression-cylinder, as indicated in the dot- 130

ted lines, so that, if desired, the mechanism for supplying the colored inks can be disconnected and the machine run simply to make an ordinary black impression.

5 I have thus provided a mechanism in which the bed has the ordinary stroke and a mechanism in which the color-plates will register very accurately with each other, as they are all carried by a single integral carrier.

10 It is an advantageous construction to have the transfer-cylinder L out of contact with the color-design-plate cylinder when inking the form and so controlled as to only contact with the color-design-plate cylinder for one

15 revolution of the latter. As the color-design-plate cylinder makes two revolutions for each cycle, each plate will be twice inked; but by said construction the plates will only contact once with the transfer-cylinder in each

20 cycle. This gives a very even and perfect registering and blending, if desired, of the inks. By having the transfer-cylinder only contact with one part at a time distortion of and strain on the transfer-cylinder is

25 avoided.

Although the invention is shown and described in connection with a two-revolution impression-cylinder, it is obvious, of course, that the same is equally applicable to a machine employing what is known as the "stop-cylinder."

30 As many color-plates as desired can be arranged on the color-design-plate cylinder. These plates may occupy the whole or any 35 part of the surface of the color-design-plate cylinder circumferentially or axially, so that the entire printing-form or any part thereof may be inked to give a multicolor-impression. Thus, for example, if the form is made 40 up to print a number of pages one or more or all of the pages can be inked to print in colors, or if the printing-form is made up of large size a plate or a cut therein may be inked to make a multicolor impression therefrom.

45 The arrangement of the plates is controlled by the design it is desired to print.

The details herein shown and described may be greatly varied by a skilled mechanic without departing from the scope of my invention as expressed in the claims.

50 Having thus fully described my invention, what I claim, and desire to secure by Letters Patent, is—

1. The combination in a multicolor-printing machine, of an impression-cylinder, a reciprocating bed coöperating therewith and carrying a printing plate or form, a color-design cylinder capacititated to receive a plurality of color-design plates circumferentially, 55 a separate inking apparatus for each color-design plate, means for taking the ink from each inking apparatus to the color-design-plate cylinder so that the ink from each apparatus will be applied to one color-design 60 plate only, and a rotary transfer-cylinder on

which the colors are registered circumferentially and axially to make a positive of the multicolor imprint and from which the positive is applied to the printing plate or form.

2. The combination in a multicolor-printing machine, of an impression-cylinder, a reciprocating bed coöperating therewith and carrying a printing plate or form, a color-design cylinder capacititated to receive a plurality of color-design plates circumferentially, 70 an inking apparatus for each color-design plate coöperating with said color-design-plate cylinder, a transfer-cylinder on which the colors are registered circumferentially and axially to make up a positive of the multicolor imprint, and means for moving the transfer-cylinder to contact with the form on the bed as the bed moves in one direction, and to clear the form as the bed moves in the opposite direction to apply the positive to 80 the printing plate or form.

3. The combination in a multicolor-printing machine, of an impression-cylinder, a reciprocating bed coöperating therewith and carrying a printing plate or form, a color-design cylinder continuously revolving in one direction and capacititated to receive a plurality of color-design plates circumferentially, 85 an inking apparatus for each color-design plate, a transfer-cylinder on which the colors are registered circumferentially and axially geared to the color-design-plate cylinder, arranged to take the ink from all the color-design plates to make a positive of the multicolor imprint, and means for moving 90 the transfer-cylinder to contact with the form on the bed as the bed moves in one direction, and to clear the form as the bed moves in the opposite direction to apply the positive to the printing plate or form.

4. The combination in a multicolor-printing machine, of an impression-cylinder, a reciprocating bed coöperating therewith, a color-design-plate cylinder capacititated to receive three color-design plates and a plate 100 for black ink circumferentially, four inking apparatuses coöperating with said color-design-plate cylinder, and a transfer-cylinder on which the colors are registered circumferentially and axially arranged to take ink 105 from the plates, and apply the same to the printing-form carried by the bed.

5. The combination in a multicolor-printing machine, of an impression-cylinder, a reciprocating bed coöperating therewith, a 110 back delivery for the sheets, a color-design-plate cylinder arranged front of the impression-cylinder and adapted to receive a plurality of color-design plates circumferentially, an inking apparatus for each color-design 115 plate coöperating with the color-design-plate cylinder, and a rotary transfer-cylinder arranged to take ink from the color-design plates, and apply the same to the printing-form carried by the bed.

6. The combination in a multicolor-printing machine, of an impression-cylinder, a reciprocating bed coöperating therewith, a color-design-plate cylinder adapted to receive a plurality of color-design plates circumferentially, a plurality of inking apparatuses coöperating with the color-design-plate cylinder, a transfer-cylinder mounted in pivoted arms, and geared to the color-design-plate cylinder, and means for moving the transfer-cylinder so that the same will take ink from the color-design plates and apply the same to the form carried by the bed.

7. The combination in a multicolor-printing machine, of an impression-cylinder, a reciprocating bed coöperating therewith, a

color-design-plate cylinder capacitated to receive a plurality of color-design plates circumferentially, an inking apparatus for each color-design plate, a rotary transfer-cylinder, and means for moving the transfer-cylinder so that it will alternately and separately contact with the color-design-plate cylinder and the printing-form carried by the bed.

In testimony whereof I have hereunto set my hand in the presence of two subscribing witnesses.

LOUIS W. SOUTHGATE.
